UNITED STATES PATENT OFFICE.

D. BERT HARTLEY, OF CHICAGO, ILLINOIS.

MECHANICAL MOVEMENT.

SPECIFICATION forming part of Letters Patent No. 278,011, dated May 22, 1883.
Application filed November 24, 1882. (No model.)

To all whom it may concern:

Be it known that I, D. BERT HARTLEY, of Chicago, county of Cook, and State of Illinois, have invented certain new and useful Improvements in Mechanical Movements, of which the following is a full, clear, and exact description, that will enable others to make and use the same, reference being had to the accompanying drawings, and to letters of reference marked thereon, forming a part of this specification.

The object of this improvement is to provide a substitute for the ordinary crank in converting a rotary into a reciprocating motion, as will be hereinafter more fully set forth.

Figure 1 is a side elevation embodying my improvement; Fig. 2, a longitudinal sectional view in the plane 3 3, Fig. 3, looking outward; and Fig. 3, a vertical transverse section in the plane 2 2, Fig. 2.

Referring to the drawings, A represents the fly-wheel, A' the main shaft, and A² the connecting-rod, of a steam-engine. The continuous or endless rack B is attached to the outer end of the connecting-rod A². This rack is of an oval elongated form, and is provided with a continuous row of gear-teeth on the inner circumferential surface, as shown in Fig. 2 of the drawings. This rack is provided with the central hub, C, which is of a form corresponding to that of the rack, and is secured in relation thereto by the strengthening-ribs a. These radiating ribs project outward a little, as shown in Fig. 3 of the drawings. The hub C is provided with the inner projecting elongated bearing, a', which has a continuous reciprocating bearing on the outer end of the main shaft projecting a little beyond the plane of the pinion D, placed upon and rotating with the main shaft. The pinion D engages with and rolls around on the inside of the rack B, these parts having a continuous engagement with relation to each other. The elongated bearing a' serves as a guide in retaining the pinion and rack in

proper relation to each other, particularly when the under side of the bearing a' is in contact with the end of the main shaft, as at this time the pinion and rack would be more liable to become disengaged than at any other point. The rack, of course, will be of the same length as that of the stroke of the piston; but by varying the length of the stroke the main driving-shaft of the engine, or other body to which the device is attached, may make one or more revolutions while the reciprocating body is making a single stroke.

I am aware that mechanical movements have been made with a pinion with fixed bearings and for its shaft moving upon an oval rack that alternately rises and falls to meet the pinion, which is supported by pivoted rods to accomplish this movement. My device differs from that form, in that I dispense with the pivoted bars, which are liable to become worn or useless. Furthermore, such a movement is not adapted to be used on a steam-engine. Therefore,

What I claim is—

1. In a mechanical movement, the combination, with a hub, C, having elongated bearing a', radial ribs a, and an elongated rack, of a pinion having its cogs in contact with the shaft and the end of its shaft in contact with the elongated bearing, substantially as described.

2. In a mechanical movement, the combination of a connecting-rod or other immediate connection between a rotary and reciprocating body having an elongated rack at one end, provided with arms attached to an elongated hub, and a pinion which meshes with said rack and has a bearing on said hub, substantially as described.

D. BERT HARTLEY.
